UNITED STATES PATENT OFFICE.

HIRAM W. FRENCH, OF ALLEGHENY, PENNSYLVANIA.

FELTING-MACHINE.

SPECIFICATION forming part of Letters Patent No. 425,604, dated April 15, 1890.

Application filed November 18, 1889. Serial No. 330,644. (No model.)

To all whom it may concern:

Be it known that I, HIRAM W. FRENCH, a citizen of the United States, residing at Allegheny, in the county of Allegheny and State of Pennsylvania, have invented certain new and useful Improvements in Felting-Machines; and I do hereby declare the following to be a full, clear, and exact description of the invention, such as will enable others skilled in the art to which it appertains to make and use the same.

My invention relates to a reciprocating felting-machine, and has for its object the treatment of a larger amount of material in a more efficient manner than has hitherto been accomplished.

With this end in view my invention consists in the peculiar features and novel combinations more fully described hereinafter, and pointed out in the claims.

In the accompanying drawings, Figure 1 represents a front elevation of my machine; Fig. 2, a side elevation; Fig. 3, a top view; Fig. 4, a perspective view of the steaming-table; and Figs. 5, 6, 7, 8, and 9, detail views.

The reference-letter *a* represents the felt-receiving bed-plate, which is secured to and supported upon the channel-beams *f*, and these beams are anchored to the foundation *b* by means of bolts *c*, passing through lateral flanges *d* *d'*. A reciprocating platen *m* operates over the bed-plate *a*, being actuated by driving-rod *i*, having one end yoked to double eccentrics upon the drive-shaft *g* and the other end connected to a transverse rod *j*, mounted in lugs *k*, rising from the top of the platen. The drive-shaft *g* is mounted in boxes *o'* in the top of standards *e*, cast integral with and rising from the channel-beams *f*. Two pulleys *n*, located, respectively, upon opposite ends of the shaft, give it a smooth and uniform motion, while the rigid channel-beams and standards add great strength and durability to the machine. Each of the double eccentrics comprises an offset *h* in the drive-shaft *g* and an adjustable eccentric collar *u'* surrounding this offset. The driving-rod *i* yokes *u* embrace the eccentric collars *u'* and are confined thereon by annular bosses *v*, cast integral with the collar. One of the bosses *v* is provided with set-screws *w*, passing through a threaded aperture and enter-

ing an annular groove *x* in the offset *h*. This arrangement prevents the collar from slipping laterally and permits it to be adjusted around the offset for the purpose of regulating the throw of the driving-rod, and hence the plate, for by shifting the collar to the position shown in Fig. 8 the longest stroke is obtained, and by shifting it to the position shown in Fig. 9 no stroke whatever will be given. Intermediate adjustments permit the length of stroke to be regulated with the greatest precision, whereby the machine can be adjusted to operate upon stock of any desired thickness.

Without the annular grooves in the offset *h* the adjustment of the eccentric collar would be more difficult and the end of the set-screws would indent and burr the shaft; but by its employment these difficulties are avoided. The groove *x* serves to guide the collar in a true path around the offset during the adjusting operation by means of the rounded ends of the screws *w*, which enter the groove, and by this arrangement the burring of the shaft is prevented.

The opposite ends of the platen *m* are provided with buffers *H* *H'*, which impinge, respectively, upon the stops *r* and *r'*, and are depressed at the end of each backward and forward movement of the platen for the purpose of deadening the shock incident to the reversal of movement, and their reactive force greatly assists in giving it the initial movement in reversing the stroke. Hence it will be seen that this feature lessens the strain upon the machinery and renders its operation smooth and uniform.

The bottom of the platen *m* is provided with small corrugations *m'*, running in a direction parallel with the motion of the platen, and the bed-plate *a* is also provided with similar corrugations *f'*, extending transversely to those in the upper platen. These grooves hold the material firmly upon the bed-plate during the process of forming.

In order to raise the top plate for the insertion and removal of material, a pair of jacks *s* are arranged upon the front and rear of the machine, as will be seen in Figs. 1, 2, and 3. Each of these jacks comprises a hollow pedestal *y*, anchored to the foundation *b*, a vertical bar *s'*, with a rack *w'* in its side and

screw-seat f'' in its top, a pinion m'' , keyed to a shaft v' , mounted in the offset m''' , and a lever z' , rigidly secured to the pinion-shaft v' . The two jacks at the front and the two at the rear each have the upper ends of their levers z' connected by a horizontal link a' , whereby all four jacks are operated in unison to elevate both ends of the top plate at the same time. Hand-levers d'' extend laterally from the pinion-levers z' , and each is provided with adjustable counterbalancing-weights e' , which weights have sufficient gravity to overbalance and hold the top plate in raised position when the levers are depressed. The weight may be adjusted to hold the plate at any desired height by moving it back and forth upon the hand-lever.

Prior to subjecting the stock to the action of the felting or hardening process beneath the reciprocating platen m , the crude material 1, which has been previously carded in the usual way, must be steamed, and this is accomplished by the means now to be described. Upon the left of the hardening-plate is located a long steaming-table 2, over which an apron 7, of burlap, passes. This apron receives the several layers of crude material and is drawn beneath the reciprocating platen m by means of the windlass 3, located upon the opposite side of a receiving-table 4. This steaming-table consists of a shallow metallic box having a sloping bottom for the purpose of draining off condensed steam and a top formed of longitudinal strips 5 of iron with smooth upper surfaces. These strips are placed a short distance apart and form a grid through which the steam freely passes into the material. Steam is supplied to the table through pipes 6.

The preferred construction of my machine having been set forth, I will now proceed to describe its operation. The crude material, which has first been formed by carding and rolled into bats, is unrolled and spread upon the feeding-apron 7 and placed over the steaming table so as to completely cover it, in order that the steam will thoroughly permeate all its parts before passing beneath the hardening-platen m . After having been thoroughly steamed the windlass is set in operation and the steamed portion of the felt drawn beneath the platen. The hand-levers to the jacks are then raised, so that the platen descends upon the material, and the driving-shaft is set in motion. When the platen has been reciprocated a sufficient length of time to properly harden the material and form the cloth, the jacks are brought into operation and the platen raised clear of the material.

During the hardening process that part of the stock which lies over the steaming-table is undergoing the steaming operation. Therefore when the platen is raised another portion of the material is always in readiness to be drawn beneath the platen to undergo the hardening process. By this arrangement no time is lost in steaming the material, and the shallow box

and grid permit the material to receive the full benefit of the steam in a much more efficient manner than has hitherto been known. 7c

By my arrangement an exceedingly large amount of material can be treated at a time, and the amount can be still further increased by making the drive-shaft longer and the bed and platen larger. It is also evident that 75 many slight changes which might suggest themselves to a skilled mechanic could be resorted to without departing from the spirit and scope of my invention; hence I do not limit myself to the exact construction shown. 80

Having thus described my invention, what I claim as new, and desire to secure by Letters Patent, is—

1. In a felting-machine, a stationary bed-plate provided with grooves, in combination with a reciprocating platen having grooves running transversely to those in the bed, and means, substantially as described, for actuating the platen, in the manner and for the purpose as described. 85

2. The combination, in a felting-machine, of a stationary bed-plate, a reciprocating platen, elastic buffers, a drive-shaft provided with revolving cams, rods connecting the cams with the shaft, and means, substantially as described, for adjusting the throw of the platen, all arranged and adapted to operate substantially as described. 95

3. In a felting-machine, the combination of a reciprocating platen located over a stationary bed-plate, lifting-jacks having pinions and levers for elevating said platen and provided with a vertically-adjustable seat, a link connecting the free ends of said levers, whereby they can be moved in unison, and a hand-lever, all arranged and adapted to operate in the manner and for the purpose substantially as described. 100

4. In combination with a bed-plate and reciprocating platen, a stationary steaming-table located at one side of said bed-plate and platen, and means, substantially as described, for drawing the material across the table and between the platen and bed-plate, whereby one portion of the material is steamed prior 115 to receiving pressure, in the manner and for the purpose substantially as described. 110

5. In a felting-machine, the combination of a reciprocating platen located over a stationary bed-plate, lifting-jacks provided with 120 pinions and levers for elevating said platen, a link connecting the free ends of the levers together, and a hand-lever provided with an adjustable weight, all arranged and adapted to operate in the manner and for the purpose 125 described.

6. In a felting-machine, a drive-shaft having eccentrics provided with adjustable eccentric collars, in combination with a platen provided with drive-rods and reciprocated by 130 said eccentric, in the manner and for the purpose described.

7. In a felting-machine, the combination, with a reciprocating platen and driving-rods,

of a drive-shaft having eccentrics provided with adjustable eccentric collars, whereby the length of the stroke of said plate is regulated, in the manner and for the purpose substantially as described.

8. In a felting-machine, a drive-shaft having an eccentric provided with an annular groove, in combination with an adjustable eccentric collar provided with set-screws having their ends arranged to enter said groove, in the manner and for the purpose substantially as described.

9. In a felting-machine, a steaming-table having a sloping bottom and open top, in combination with steaming-pipes arranged and adapted to operate in the manner and for the purpose substantially as described.

In testimony whereof I affix my signature in presence of two witnesses.
